(57) **CLAIM**

The ornamental design for a box for electrical elements, as shown and described.

DESCRIPTION

The present design application is related to U.S. Design patent application Ser. Nos. 29/551,025 and 29/551,026, both filed on the filing date of this application.

FIG. 1 is a front perspective view of a box for electrical elements of the present design;

FIG. 2 is an exploded front perspective view thereof;

FIG. 3 is a rear perspective view thereof;

FIG. 4 is a rear elevation view thereof;

FIG. 5 is a right side elevation view, the left side being a mirror image thereof;

FIG. 6 is a top plan view thereof; and,

FIG. 7 is a bottom plan view thereof.

The broken lines in the drawings are for purposes of illustrating unclaimed elements of the box for electrical elements and form no part of the claimed design.
